INJECTION ENGINE

Franz Lang, Munich, Germany, assignor to
Lanova Aktiengesellschaft, Vaduz, Liechten-
stein

Original application December 1, 1930, Serial No.
499,223. Divided and this application June 30,
1933, Serial No. 678,354. In Germany April 8,
1930

1 Claim. (Cl. 123—32)

My invention relates to a fuel injection internal combustion engine of the type which embodies an air chamber in which fluid is compressed during the compression stroke of the piston and from which the fluid issues during the working stroke of the piston.

This application is a division of my copending application Serial No. 499,223, filed December 1, 1930, for Fuel injection internal combustion engines.

The instant invention contemplates an improved combustion chamber shape and fuel nozzle air chamber and valve relationship, to the end of obtaining effective mixing of the charge, keeping crude oil from coming between the piston and cylinder walls, and accomplishing simplicity of construction.

My invention is illustrated in the accompanying drawing, in which

20 Figure 1 is a vertical axial sectional view of those portions of the engine with which my invention is concerned;

Figure 2 is a vertical axial sectional view taken at right angles to the plane of Figure 1; and

25 Figure 3 is a horizontal sectional view taken on the plane of the line E—F of Figures 1 and 2, looking downwardly, the lines A—B and C—D indicating the planes on which Figures 1 and 2, respectively, are taken.

30 The drawing shows the cylinder, the piston which reciprocates in the cylinder, and the head. The fuel nozzle is shown at *a*, the air chamber at *b*, the combustion chamber at *c*, and the inlet and outlet valves at *d* and *e*, respectively.

35 The combustion chamber *c* formed in the head, is of circular section, in one vertical plane, and the nozzle and air chamber are disposed on opposite sides of the combustion chamber in this vertical plane. The air chamber opening is flared toward the combustion chamber and the wall of this flared opening merges with the circular wall of the combustion chamber in such a way that a pear-shape results in said vertical plane as shown in Figure 2. At right angles to the above mentioned vertical plane, the combustion chamber is rectangular in cross section, as shown in Figure 1, and the inlet and outlet passages communicate with the combustion chamber

as is clear from Figures 1 and 3. The inlet and outlet elements lie horizontally and are of elbow formation, as shown in Figure 3, and the stems of the inlet and outlet valves *d* and *e*, respectively, are appropriately mounted in bosses formed with 5 the elbows.

As clearly shown in the drawing, the combustion chamber *c* communicates downwardly with the cylinder over the central portion of the piston, the remainder of the area of the piston top coming fairly close to the head, as shown.

Upon the compression stroke of the piston, fluid from above the piston is compressed in the chamber *b*, and upon the working stroke of the piston this fluid issues from the chamber at high velocity, 15 the stream of fluid being directed toward the opposite combustion chamber wall from which the fuel injection comes, and the charge is then whirled centrally into the cylinder, as indicated in Figure 2.

20 Suitable mechanism is of course provided to cause the valves to operate at the proper time in the cycle, and suitable mechanism is of course provided to cause the nozzle *a* to inject fuel into the combustion chamber at the proper time in 25 the cycle, beginning with the final compression.

I claim:—

In an injection engine, a cylinder and a piston operating therein, a combustion chamber of rectangular shape in vertical cross-section and of 30 approximately pear shape in vertical lengthwise section overlying and communicating with the cylinder centrally thereof through a restricted slot-like opening of rectangular shape in plan, the side walls of said chamber being flat and 35 vertical, inlet and exhaust valves mounted coaxially in said side walls on an axis normal to the cylinder axis, an air storage chamber opening into the combustion chamber at the tip end of the latter through a restricted orifice, and a 40 fuel injection nozzle opening into the combustion chamber at the opposite end of the latter, said nozzle being disposed coaxially with said orifice on an axis normal to the cylinder axis, the common axis of said valves and the common axis 45 of said nozzle and said orifice being disposed in a common plane substantially normal to the cylinder axis.

FRANZ LANG.
